UNITED STATES PATENT OFFICE.

EMIL DEISTER, OF FORT WAYNE, INDIANA.

DESIGN FOR A TIRE.

Application filed November 12, 1923. Serial No. 7,746. Term of patent 14 years.

To all whom it may concern:

Be it known that I, EMIL DEISTER, a citizen of the United States, residing at Fort Wayne, in the county of Allen and State of Indiana, have invented a new, original, and ornamental Design for Tires, of which the following is a specification, reference being had to the accompanying drawing, forming part thereof.

I claim:

The ornamental design for a tire as shown.

EMIL DEISTER.
